PATCH

Eugene Dugaw, Tacoma, Wash.

Application September 22, 1941, Serial No. 411,865

2 Claims. (Cl. 20—93)

This is a continuation in part of the application filed June 1, 1936, Serial Number 82,716, issued as Patent Number 2,168,766 on August 8, 1939 and of application filed August 7, 1939, Serial Number 288,880, issued as Patent Number 2,259,806 on October 21, 1941.

This invention relates to patches adapted to be applied to veneer, plywood panels, or wood boards to fill a cut-out space therein from which a pitch-pocket, knot, or other defect in the wood of the panel has been removed.

Many attempts have been made to make a patch suitable for the hand patchers, a patch that would fit perfectly into a previously prepared cut out space from which a knot, pitch-pocket or other defect has been removed from the wood of the panel, a patch that would fit perfectly into a previously prepared cut out space or hole, a patch that would leave no hole or glue stain at its ends after insertion into the patch hole, heretofore the patches used in the hand patching method have fitted poorly at their ends, thereby leaving a small hole which caused a glue-stain at the ends of the inserted patch, thus lowering the grade and salability of the manufactured product, and caused many complaints, extra expense, much loss in time, thus lowering the amount of production and increasing the cost of the individual panels. Therefore in order to avoid having a hole, or glue-stain at the ends of these inserted patches, I have devised a patch with an improved end or tip, the aforesaid end or tip to be known as a tail or sliver.

The hole which this tail or sliver in my improved patch is designed to fill, at the end of the previously prepared hole, has a number of causes, the most troublesome one being, the more or less square edge of the patch-hole cutting tool at the end of the cutting edge, required to sustain the edge of the patch-hole cutting tool in its proper form, through which the patch-hole is not brought entirely to a point. Therefore when the old style patch is inserted a hole remains open at the patch end. Another cause is the tendency of the patch-hole cutting tool to slip sidewise when struck with a hammer, while performing the cutting operation.

It is the general object of my invention, to provide a patch with a greatly improved end or ends, by the addition of a projecting tail like sliver (more or less ribbon like in form) at each end of the patch, thereby creating a patch that will fit perfectly into a previously prepared patch-hole and completely close the hole that would

otherwise have been left open in the finished product, thereby causing glue to ooze out and cause a glue stain, and my invention eliminates this trouble.

5 It is the further object of my invention to provide a patch that can be rapidly and accurately manufactured in a single operation, thereby cutting down the cost of the individual patches and to enhance the value of the patched piece, also 10 to provide a patch with a beveled edge, whereby it may be forced in tightly.

I attain these and other objects, by the improvements herein described and illustrated in the accompanying drawing, of which—

15 Fig. 1 is a detail perspective view of a patch showing the top or face side.

Fig. 2 is a plan view of the patch shown in Fig. 1, showing the bottom side.

Fig. 3 is a plan view of a section of the patch 20 shown in Fig. 4 in the direction of the arrows 3—3 of Fig. 4.

Fig. 4 is a top plan view of a patch similar to the patch shown in Fig. 1 except that the two slivered portions of the edge curvature extended 25 are on the same side edge of the patch.

Fig. 5 is a bottom plan view of the patch shown in Fig. 4.

Fig. 6 is a plan view of the top side of a patch similar to the ones shown in Figs. 1 to 5, except 30 that it discloses a different form of side edge curvature.

Similar numerals of reference refer to similar parts throughout the several views.

The patch 1 shown in Figs. 1 and 2 is formed 35 with two flat opposite parallel sides, known as the top and the bottom of the patch 1, and this patch 1 has two similar curved side edges 2 and 3 each having the same radius and approaching each other at sharp angles and joined 40 to each other by very short slivered edge portions 4 and 4 with one at each end of the patch 1 and each split or short slivered edge portion 4 is on the opposite or opposed similar side edge curvatures 2 and 3 as shown in Figs. 1 and 2 45 with the slivered edge portions 4 and 4 running parallel to the grain of the wood in the patch and thereby forms the two side edge curvature completing the perimeter of the patch and extending the tip of the patch to form the tail or splinter 5.

In the patch shown in Figs. 3 to 5 the patch 9 is formed with two similar curved side edges 6 and 7 the similar curved side 7 being longer than the similar curved side 6, and both side edges have the same radius, the side edge 6 is

extended at both ends by the sliver 8 and 8 to join at both ends the opposite side edge curvature 7 thereby forming an extended end, the tails or splinters 10.

In the patch 11 shown in Fig. 6 the same structure is incorporated therein as is shown in Figs. 1 to 5, except that it has a different form to illustrate the various shapes that might be used.

Thus it will be seen from the foregoing disclosure that the patch is an improvement over the old patches in use and disclosed in Welch's patent in Figs. 9 and 10, dated Sept. 20, 1932, as Patent No. 1,878,081, and in Stager, 1,629,595, dated May 24, 1927, Fig. 15.

It is of course understood that many variations may be made in the details of construction of the above described patch, without departing from the spirit of my invention as outlined in the appended claims.

Having therefore, described my invention what I claim and desired to secure by Letters Patent, is:

1. A patch having curved side edges, approaching each other on acute angles and joining in a sliver projecting from each point of junction.
2. A patch having curved side edges, approaching each other on acute angles and joining in a split at each point of junction, wherein a small tail is formed at each end of the patch and wherein one side edge of said tail conforms to the same curvature as the edge of the patch it is the continuation thereof, and wherein the opposite edge of said tail is formed by a split parallel the grain and connects the two opposite side edge curvatures of said patch at each point of junction.

EUGENE DUGAW.
